UNITED STATES PATENT OFFICE.

AUGUST SOFFEL, OF NEWARK, NEW JERSEY.

DESIGN FOR A HANDLE FOR BUTTON-HOOKS.

SPECIFICATION forming part of Design No. 26,970, dated April 27, 1897.

Application filed March 12, 1897. Serial No. 627,249. Term of patent 3½ years.

To all whom it may concern:

Be it known that I, AUGUST SOFFEL, a citizen of the United States, residing at Newark, in the county of Essex and State of New Jersey, have invented and produced a new and original Design for Handles for Button-Hooks and Like Articles, of which the following is a specification, reference being had to the accompanying drawing, which shows a side view of my newly-designed handle applied to a button-hook.

The leading feature of my design consists of a groundwork of flowers covering the upper portion of the handle and ribs extending therefrom to the lower end of the handle.

Referring to the drawing, A represents the handle of a button-hook or other like article,

the upper end thereof being ornamented, as shown at B, and carrying a groundwork or bed of flowers C, covering the upper portion 20 of the handle and surrounding a shield D.

E represents ribs formed on the lower portion of the handle and extending from the ornamentation C to or within a short distance of the lower end of the handle. 25

What I claim is—

The design for a handle for button-hooks, and similar articles, substantially as herein shown and described.

AUGUST SOFFEL.
